CLAIM

The ornamental design for a laptop computer, as shown and described.

DESCRIPTION

FIG. 1 is a front perspective view of a laptop computer, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof unfolded in an alternate configuration;

FIG. 9 is another front perspective view thereof unfolded in another alternate configuration;

FIG. 10 is a front perspective view of FIG. 8, shown with unclaimed environmental structure; and,

FIG. 11 is another front perspective view of FIG. 8, shown with unclaimed environmental structure.

The broken lines shown in the drawings represent portions which form no part of the claimed design. The even-dash broken lines illustrate portions of the laptop computer and form no part of the claimed design. The additional set of broken lines in FIGS. 10-11 illustrate environment and form no part thereof.

1 Claim, 11 Drawing Sheets
